UNITED STATES PATENT OFFICE

2,578,233

HANDLE AND BRUSH HOLDER FOR PAINT CANS

Dallas E. Entsminger, Hilton Village, Va.

Application March 3, 1947, Serial No. 731,982

5 Claims. (Cl. 220—90)

1

This invention relates to a handle and brush holder for a paint can and has for its primary object to provide a convenient handle and brush holder which may be easily and quickly attached to or detached from a paint can or like receptacle having an inwardly extending annular flange at its open end.

Another object is to provide a convenient brush rest and scraper bar upon which a brush may be supported with its bristles suspended over the open end of a paint can to prevent paint carried by the brush from being distributed over the outside of the can.

The above and other objects may be attained by employing this invention which embodies among its features a handle, an outwardly and downwardly inclined extension at one end of the handle, a can engaging shield at the end of the extension remote from the handle, said shield extending toward the general plane of the handle and lying in a plane substantially perpendicular thereto, a hook at the end of the shield remote from the extension adapted to overlie the flange of the can at the open end thereof, the end of the hook remote from the shield being adapted to enter the open end of the can and an ear projecting laterally from each side of the portion of the hook which enters the can for engagement beneath the inwardly extending annular flange of the can.

In the drawings:

Figure 1 is a perspective view of a paint can handle and brush holder embodying the features of this invention;

Figure 2 is a top plan view of an open paint can illustrating this handle and brush holder mounted thereon;

Figure 3 is a vertical sectional view taken substantially along the line 3—3 of Figure 2, and

Figure 4 is a side view of the brush holder and paint can handle.

Referring to the drawings in detail, this improved paint can handle and brush holder comprises a handle portion 10 which in the present embodiment is formed of a sheet of metal having convergent side walls, and along opposite side edges rolled portions 11 which are adapted to enclose a pair of spaced convergent arms 12 of a wire structure to be more fully hereinafter described. As illustrated the sheet metal body 10 is preferably concave longitudinally to form a trough in which the handle of the paint brush is adapted to rest.

The wire structure above referred to comprises a cross bar 13 provided at opposite ends with

2

downturned legs 14. The bar 13 lies in a horizontal plane substantially coincidental with the general plane of the handle 10, and formed at the lower ends of the legs 14 are outwardly extending ears designated generally 15 comprising return bends 16 which lie in a horizontal plane below the bar 13, and project longitudinally with relation to the bar. The ends of the return bends 16 opposite those connected with the legs 14 are provided with upturned extensions 17 terminating at their upper ends in horizontal members 18 which extend toward the handle in a plane intermediate the plane of the handle and the ears 15. Formed integrally with the horizontal members 18 at the ends opposite the upturned members 17 are downwardly extending convergent bars 19 which cooperate to form a shield which lies against the outer side of a paint can when the device is in place thereon. The lower convergent ends of the bars 19 have formed integrally therewith upwardly divergent extensions 20 which incline upwardly and outwardly away from the shield formed by the members 19 and are joined to the bars 12 of the handle 10. A suitable binding loop 21 encircles the members 20 adjacent their lower convergent ends to hold the parts in properly assembled position.

In use it will be understood that the ears are entered into the can mouth with the handle 10 in a substantially vertical position and the unit or holder as a unit is moved radially until the ears 15 engage beneath the flange F of a paint can C when the handle and paint brush holder is then rotated about the axes of the ears 15 to bring the shield formed by the convergent members 19 and designated generally 22 against the outer side of the can. When thus positioned on the paint can C the bar 13 will form a convenient rest for the bristles or ferrule of a paint brush and the handle of the brush may conveniently rest in the trough-shaped handle 10. The entire unit may be employed to lift the paint can bodily to transport it from place to place, and the bar 13 may conveniently be used to scrape the excess paint from the bristles of the brush during the painting operation. Obviously the excess paint scraped from the brush bristles will be drained into the can rather than having it dribbled over the outside surface thereof as frequently occurs when the inturned flange F is employed as the scraper.

While in the foregoing there has been shown and described the preferred embodiment of this invention it is to be understood that minor changes in the details of construction, combina-

tion and arrangement of parts may be resorted to without departing from the spirit and scope of the invention as claimed.

What I claim is:

1. A brush holder for a container of the type having an inwardly extending flange at its upper open end, said brush holder comprising a pair of V-shaped members having inner and outer legs, a handle forming member attached adjacent the upper ends of said outer legs of said V-shaped members and extending rearwardly thereof away from said inner legs of said V-shaped members, a pair of L-shaped arms each having first and second legs, said first leg of each of said arms being attached to the upper end of each of said inner legs and extending forwardly thereof to overlie the flange of a can, said second leg of each of said arms extending downwardly, an inverted U-shaped brush rest including a web portion and depending fingers, a pair of U-shaped ears connecting the lower ends of said fingers and the adjacent lower ends of said second legs of said arms, said ears extending in opposite directions and parallel to said web portion of said brush rest to underlie the flange of a can.

2. A brush holder for a container of the type having an inwardly extending flange at its upper open end, said brush holder comprising a pair of V-shaped members having inner and outer legs, a handle forming member attached adjacent the upper ends of said outer legs of said V-shaped members and extending rearwardly thereof away from said inner legs of said V-shaped members, a pair of L-shaped arms each having first and second legs, said first leg of each of said arms being attached to the upper end of each of said inner legs and extending forwardly thereof to overlie the flange of a can, said second leg of each of said arms extending downwardly, an inverted U-shaped brush rest including a web portion and depending fingers, a pair of U-shaped ears connecting the lower ends of said fingers and the adjacent lower ends of said second legs of said arms, said ears extending in opposite directions and parallel to said web portion of said brush rest to underlie the flange of a can, said web portion of said brush rest being disposed above said first legs of said arms.

3. A brush holder for a container of the type having an inwardly extending flange at its upper

open end, said brush holder comprising a pair of V-shaped members having inner and outer legs, a handle forming member attached adjacent the upper ends of said outer legs of said V-shaped members and extending rearwardly thereof away from said inner legs of said V-shaped members, a pair of L-shaped arms each having first and second legs, said first leg of each of said arms being attached to the upper end of each of said inner legs and extending forwardly thereof to overlie the flange of a can, said second leg of each of said arms extending downwardly, an inverted U-shaped brush rest including a web portion and depending fingers, a pair of U-shaped ears connecting the lower ends of said fingers and the adjacent lower ends of said second legs of said arms, said ears extending in opposite directions and parallel to said web portion of said brush rest to underlie the flange of a can, said web portion of said brush rest being greater in length than the spacing of said first legs of said arms relative to each other.

4. The combination of claim 1 wherein said outer legs of said V-shaped members and said inner legs of said V-shaped members converge downwardly towards each other, a ring disposed about the outer legs of said V-shaped members securing said outer legs to each other.

5. The combination of claim 1 wherein said outer legs of said V-shaped members and said inner legs of said V-shaped members converge downwardly towards each other, a ring disposed about the outer legs of said V-shaped members securing said outer legs to each other, said ring being disposed adjacent the apex of said V-shaped members, said ring abutting the inner legs of said V-shaped members.
